(No Model.)

T. J. BROUH.
CORSET FASTENING.

No. 447,630.

Patented Mar. 3, 1891.

Fig. 6.

INVENTOR:

Thomas J. Brough.

BY ATTORNEYS

WITNESSES:
UNITED STATES PATENT OFFICE.

THOMAS J. BROUH, OF BALTIMORE, MARYLAND.

CORSET-FASTENING.

SPECIFICATION forming part of Letters Patent No. 447,630, dated March 3, 1891.

Application filed July 8, 1890. Serial No. 358,103. (No model.)

To all whom it may concern:

Be it known that I, THOMAS J. BROUH, of Baltimore city, in the State of Maryland, have invented a new and useful Improvement in 5 Corset-Fastenings, of which the following is a specification.

My invention is an improvement in corset-fastenings; and the invention consists in certain novel constructions and combinations of 10 parts, as will be hereinafter described, and pointed out in the claims.

In the drawings, Figure 1 shows my improved fastening as in use. Figs. 2 and 3 are respectively front and rear views of the fastening. Fig. 4 is a perspective view showing the several parts of the fastening detached. Fig. 5 is a cross-section of the invention, and Fig. 6 shows the fastening with the bearing-plate omitted.

20 The invention seeks to provide a simple economical means by which to effect the pivoting of the lock-bar and the fastening thereof to the busk, as will be more fully described.

The lock A consists of a handle-like portion 25 a , which in practice is pivoted at a' . In line with this pivot a' I provide the hook-like projection a^2 , which extends to one side only of the pivot, and is adapted to engage the corset-eye. At the end next the hook a^2 the bar 30 a is formed with a circular portion B, which forms a flat bearing, and is slotted at b to enable the hook a^2 to be bent up from it, so that the handle-bar, with its hook and circular portion may be cut or stamped out of a 35 suitable sheet or plate of metal at but little expense.

The top or cap plate C is suitably secured to the corset-busk and fits over the pivoted part of the lock, being provided with an opening C' , up through which the hook a^2 projects, and which opening forms the journal-bearing, in which the shank of such hook turns in the operation of the device. The cap-plate is formed with a central portion C^2 , in which 45 the opening C' is formed, and with end wings C^3 projected from the said central portion, and having their edges at C^4 arranged to serve as stops for abutment by the handle-bar in its locked and unlocked positions.

50 It is preferred to secure the cap-plate to the busk by providing its wings C^3 with tongue-

like portions C^5 , which project through slots D in the busk, and are bent in rear thereof, thus serving to securely fasten the cap-plate to the busk without the necessity of using 55 rivets or the like. While the handle-bar may be caused to turn directly on or against the busk, as shown in Fig. 6, it is preferred to employ an under bearing-plate E, arranged under the pivoted portion of the handle-bar and 60 between the same and the busk, as the said plate E holds the handle-bar up to the cap-plate, and also forms a smooth bearing on which the handle may be easily turned.

By preference the plate E is held to the 65 busk by means of a lug or tongue e , which projects from it through a slot d in the busk, and is bent along the inner side of the busk, as shown. The eyes G of the corset-fastening are formed to receive the hook, and are secured to the busk, which supports them by means of lugs or tongues g , which project through slots f in the busk F, and are bent in rear thereof to properly secure the eyes in a simple convenient manner. 75

The operation will be readily understood. If the handle-bar be turned up, the hook will face outwardly, and the eye may be easily fitted over or removed from the hook. If the eye be fitted over the hook and the handle-bar be thrown down, the hook will be reversed and will be adjusted to secure the eye until the handle-bar be adjusted back to upper position. The handle-bar is shown as bent or arched slightly outward between its pivot and 85 its outward extremity, as thereby it may be more easily pressed by the thumb or finger from one of its positions to the other to secure or release the eye, as may be desired.

It will be seen that the cap-plate serves to 90 secure the lock-bar to the busk, and at the same time forms the pivot therefor.

Having thus described my invention, what I claim as new is—

1. In a corset-fastening, substantially as 95 herein described, the combination of the supporting-busk, the lock having a handle-bar and a hook, and the cap-plate provided with an opening through which the said hook projects and in which it journals, the said cap-plate 100 being secured to the corset over the lock and serving to secure such lock to the corset and

to form a bearing for the pivotal movement of said lock, substantially as and for the purposes set forth.

2. In a corset-fastening, the combination of 5 the supporting-busk, the lock having a handle-bar and a hook, and the cap-plate secured to the busk and having a central portion C^2 , provided with an opening C' for the hook and having wings C^3 , arranged at their edges 10 C^4 to form stop-abutments for engagement by the handle-bar in its locked and unlocked positions, substantially as set forth.

3. In a corset-fastening, the combination of the supporting-busk, the under bearing-plate 15 E, the lock arranged to turn on the plate E and provided with a hook, and the cap-plate fitted and secured over the said lock and having an opening through which the lock-hook projects and in which the shank of said hook 20 turns, substantially as and for the purposes set forth.

4. The improved corset-fastening, substantially as herein described and shown, consisting of the busk having slots D and d , the plate E, having a lug or tongue passed through 25 slot d and bent in rear of the busk, the lock placed on said plate E and having a hook-like projection and a handle-bar, and the cap-plate having a central portion C^2 , provided with opening C' for the hook and having end 30 wings C^3 , provided with edge stop-bearings C^4 for abutment by the handle-bar, and with tongues projected through the slots D and bent in rear of the busk, all substantially as and for the purposes set forth. 35

The above specification of my invention signed by me in the presence of two subscribing witnesses.

THOMAS J. BROUGII.
